UNITED STATES PATENT OFFICE.

CHARLES PAFF, OF NEW YORK, N. Y.

BUNKER.

Application filed February 14, 1920. Serial No. 358,598.

To all whom it may concern:

Be it known that I, CHARLES PAFF, a citizen of the United States, and a resident of New York, in the county of New York and State of New York, have invented certain new and useful Improvements in a Bunker, of which the following is a full, clear, and exact specification.

This invention relates to a class of structures adapted to be used for storage of coal, grain, etc.

My invention has for its object primarily to provide a bunker designed to be employed for storing grain, coal and the like whereby large quantities of the products may be accumulated at given localities for general distribution as well as being protected during intervals from exposure to weather, and which is constructed to withstand the strain of heavy loads on its interior without its walls tending to bulge or give way as is incident to bunkers and storage structures of ordinary construction. The invention consists essentially of a chamber having preferably reinforced concrete or steel walls formed of joined corner sections and intermediate sections, the corner sections being curved throughout three-quadrants thereof and the intermediate sections being semi-cylindrically curved. All of the walls are made preferably of reinforced concrete or steel so that when stressed in tension under the weight of a load the pressure at the marginal parts of the body of the contents of the chamber will be distributed in lateral directions as well as in outward directions relative to the center of the body. The chamber is supported on a trestle with passageways for vehicles, and the chamber has a bottom composed of adjacent downwardly tapered pockets each with a gate controlled outlet leading into one of the passageways to allow vehicles to be readily loaded. Above the chamber may be spaced chutes one leading toward each of the tapered sections of the bottom, in order to permit coal and grain delivered to the chamber to be evenly distributed therein, and above the chamber is a conveyer which is operable for carrying products for delivery to the chutes.

A further object of the invention is to provide a bunker of a simple, efficient and durable construction which may be made in any suitable shape and size.

With these and other objects in view the

invention will be hereinafter more particularly described with reference to the accompanying drawing forming a part of this specification in which similar characters of reference indicate corresponding parts in all the views, and will then be pointed out in the claims at the end of the description.

In the drawing, Figure 1 is a side elevation of one form of bunker embodying my invention.

Fig. 2 is a sectional view, partly in detail, taken on the line 2—2 of Fig. 1.

Fig. 3 is a front elevation of the bunker, and,

Fig. 4 is a sectional view, partly in detail, taken on the line 4—4 of Fig. 2.

The bunker has a chamber 10 which may be of any suitable size and shape, though the form of the chamber illustrated is approximately rectangular to provide side walls 11, 12 and end walls 13, 14. The walls are preferably erected of reinforced concrete or steel, and the walls include four spaced corner sections 15, 16, 17, 18 each of which is curved substantially three-quadrants thereof. Each of the side walls 11, 12 may include three substantially semi-cylindrical sections, as 19, 20, 21, and each of the end walls 13, 14 may consist of a single substantially semi-cylindrical section 22. The corner sections and intermediate sections are all joined together, as shown, so that their concavities form parts of the interior of the chamber.

The chamber 10 is supported upon a trestle or foundation, as 23, which is composed of a number of standards 24 arranged under the sections of the walls of the chamber, and these standards are spaced apart to provide passageways, as 25, which lead crosswise under spaced portions of the chamber. In the passage-ways may be laid tracks 27 for travel of cars, as 27^a, to allow of being loaded with the contents of the chamber when it is desired to transport quantities of the contents.

The chamber 10 has a bottom formed of a plurality of adjacent downwardly tapered or substantially cone-shaped pockets 28 arranged in rows. The pockets of each row are disposed so that their apices are over the tracks 27 of the passage-ways 25 of the trestle 23. In the apex of each pocket is a gate controlled outlet 29 of any appropriate type to allow convenient opening and closing of the outlets when cars are

loaded with the contents of the bunker. On the top of the chamber 10 is a roof 30 which may be of any suitable construction, such as being of a form whereby it is superposed 5 some distance above the open top of the chamber, and leading into the roof may be one or more door controlled entrances, not shown, to allow coal, grain and other products to be delivered to the chamber 10.

10 Interiorly of the roof 30 and above the open top of the chamber 10 is provided a trestle, as 31, which may be supported in any appropriate manner so that it extends preferably from end to end of the roof 30 and chamber 10. Projecting in opposite lateral directions from the trestle 31 are a number of spaced pairs of chutes 32 and 33, and these chutes may be of any suitable widths and lengths as well as being disposed 15 from the trestle on downward inclines toward the tapered pockets 28 to permit coal, grain and the like to be distributed evenly to various parts of the interior of the chamber.

20 25 In order to convey products to the trestle 31 for delivery to the chutes 32, 33 and to the chamber 10 a conveyer 34 may be provided on the trestle. This conveyer may be of any of the forms of apparatus commonly used for carrying coal or grain from cars or other vehicles at the base of the bunker to the chutes in the roof of the bunker. By providing the walls of the bunker of the types shown and described the 30 pressure at the marginal edges of the weight of the body of the contents of the chamber 10 will be distributed in lateral directions as well as outwardly because of admission of the contents into the concavities of the 35 sections of the wall. The walls of the chamber will thereby serve to withstand the strain of unusually heavy loads without tending to bulge or give way.

40 In the forgoing description, I have 45 embodied the preferred form of my invention, but I do not wish to be understood as limiting myself thereto, as I am aware that modifications may be made therein without

departing from the principle or sacrificing any of the advantages of this invention; 50 therefore, I reserve to myself the right to make such changes as fairly fall within the scope thereof.

Having thus described my invention, I claim as new and desire to secure by Letters 55 Patent:

1. A bunker, comprising a chamber supported above passage-ways, said chamber having walls composed of joined corner sections and intermediate sections, the corner sections being curved throughout three quadrants thereof and the intermediate sections being substantially semi-circular, the chamber having a bottom composed of a series of substantially cone shaped pockets 60 arranged so that the wall of each pocket serves as a separate bottom for the part of the area of the chamber embraced within and adjacent each curved section of the wall of the chamber, and gate controlled outlets 65 in the apices of the pockets, leading to the passage-ways.

2. The combination, in a bunker, of a chamber supported above passage-ways, said chamber having walls composed of joined 70 corner sections and intermediate sections, the corner sections being curved throughout three quadrants thereof and the intermediate section being substantially semi-circular, the chamber having a bottom composed of a 75 series of substantially cone shaped pockets arranged so that the wall of each pocket serves as a separate bottom for the part of the area of the chamber embraces within and adjacent each curved section of the wall of 80 the chamber, gate controlled outlets in the apices of the pockets, leading to the passage-ways, a roof on the chamber, and spaced chutes within the roof, leading into the 85 chamber.

90 This specification signed and witnessed this 13th day of February A. D. 1920.

CHARLES PAFF.
